COMBINED TABLE AND MASSAGING UNIT

George B. Ritter, Fort Worth, Tex.

Application July 11, 1958, Serial No. 51,756

Term of patent 14 years

(Cl. D83—1)

FIG. 1.

FIG. 2.

FIG. 3.

FIG. 4.

Figs. 2, 3, and 4, are on a slightly enlarged scale.

I claim:

The ornamental design for a combined table and massaging unit, substantially as shown and described.
